UNITED STATES PATENT OFFICE

EDWARD J. HOFFMAN, OF BOSTON, MASSACHUSETTS, ASSIGNOR TO ELDEEN AUTOMATIC HOSIERY MENDER INC., OF BOSTON, MASSACHUSETTS

HAND OPERATED NEEDLE

Application filed April 2, 1928, Serial No. 286,718. Renewed May 18, 1939.

This invention relates to improvements in hand-operated needles, and more particularly to needles adapted for use in repairing ravel or runs in knitted or crocheted goods, such as stockings, mittens, sweaters, textile bags, and the like.

In using devices of this kind, the repairing operation consists essentially in first inserting the end of the needle through the last loop of the ravel, then moving the needle forwardly to catch the next thread in a hook which is ordinarily provided at the point of the needle, and finally withdrawing the needle so that the second thread is drawn through the initial loop, to form a new loop. Using the newly formed loop as the first loop in the operation, this procedure is repeated until the ravel or run is completely repaired. The needles heretofore constructed for this purpose have proved objectionable for the reason that when moving the needle forwardly with speed it is not always possible to prevent the tip of the latch from moving down below the next thread with the result that very often the tip of the latch instead of the hook is engaged by this latter thread and closed by it without any thread being in the hook. The original loop accordingly slips over an empty hook causing the work to unravel further thus undoing a considerable portion of the work already done and also causing a considerable loss of time in making it necessary to start the work all over again. Also very often the hook engages two or more succeeding threads instead of one thus resulting in faulty work which has to be undone and redone and requiring very close visual attention on the part of the operator resulting in a strain on the operator's eyes.

It is accordingly the principal object of this invention to provide a needle having a stop member intermediate its ends, so arranged that just as the first loop is passing over the tip of the latch the stop member will meet the next thread transversely and prevent the

tip of the latch from proceeding forwardly below said thread, thus obviating all possibility of the tip of the latch engaging with this latter thread. Also the hook is prevented from any further progress forwardly so that it will catch only one succeeding thread on the next upward movement.

A preferred embodiment of this invention and its method of use are illustrated in the accompanying drawings in which:

Fig. 1 is a side elevation of the improved needle;

Fig. 2 is a front elevation thereof;

Fig. 3 is a side elevation opposite to that of Fig. 1; and

Figs. 4, 5 and 6 show the several steps in the repairing operation.

The device comprises a body portion 7 which is made of fused metal or other suitable rigid material and a steel needle 8 fixed at one end within the body portion and having a curved hook 9 at its outer end. A latch or bridge 10 is loosely pivoted to the needle in proximity to the hook 9 so that it may be swung forwardly to close the hook as shown in Figs. 1 and 3, or backwardly to lie alongside of the needle.

Fixed also in the body portion 7 and extending parallel to the needle approximately half way toward its hook, is a spring steel clasp member 11 having its outer end bent transversely of the needle to form an abutment 12 which serves as a thread stop member although this may take various other forms.

The operation of the improved needle is illustrated in Figs. 4, 5 and 6 which show different positions of the needle when worked by hand upon a very loosely knitted fabric. The process illustrated may, however, be practiced in the same manner with closely knitted material. Assuming that loop 13 is the last existing loop at the end or top of a run in the goods, the point of the needle is first inserted downwardly through this loop

in such manner that the yarn or thread passes upwards on the shank of the needle. The latch 10 will be carried toward the shank of the needle by its engagement with loop 13 until the thread 4 slips over its end and between the shank and the resilient clasp 11. At this instant the tip of the latch will be disposed rearwardly of the stop 12, as the point of the needle is pushed forwardly to permit the hook 9 to catch under the next thread 14, of which the new loop is to be formed. This position is shown in Fig. 4, from which it will be noticed that the stop member 12 has met the thread 14, thereby restraining further forward movement of the needle as a whole and thus preventing the tip of the latch from proceeding forwardly beyond and catching under the thread 14 and accordingly avoiding premature closing of the latch.

20 The needle is then drawn rearwardly, permitting the thread 14 to be caught by the hook 9. Loop 13 will slide forwardly of the needle catching under the tip of latch 9 and closing the latch so that thread 14 is secured within the hook 9. Fig. 5 shows the position of the thread and needle elements just before the latch is closed. A further rearward and upward pull upon the needle will draw the thread 14 through loop 13 to form a new loop 15. When the new loop has been formed the latch will again be opened by reason of its inertia upon the sudden cessation of the rearward pull of the needle, and the needle is then in position to repeat the operation. See Fig. 6.

40 It will be understood that these operations are usually performed at great speed and with a minimum of visual attention on the part of the operator. For this reason the provision of the stop member 12 is a cardinal feature of my invention, because it not only prevents the tip of the latch from proceeding forwardly beyond thread 14 and being closed 45 by it prematurely, but it also impedes forward progress of the needle so that more than one thread will not be caught by the hook 9. The needle is pulled rearwardly with a quick jerk and sudden stop, so that the latch is thrown backward to open position, as in the 50 last operation above described. Thus, without sacrificing any of the advantages of the devices heretofore in use, I have devised an improved, hand operated repairing needle 55 which saves many delays which frequently have heretofore resulted because, without fault of the operator, the work had to be stopped to correct mistakes due to faulty construction of the prior devices.

60 I claim:

1. A device of the character described comprising a needle having a hooked end adapted to pass through the initial loop of the fabric to be repaired and to engage a succeeding thread in said fabric, a latch pivoted to

the needle in proximity to its hooked end and adapted to close upon said hook to retain said succeeding thread therein, and a stop member fixed transversely of the needle rearwardly of and adjacent the latch pivot, 70 said stop member being adapted to meet said thread during forward progress of the needle, thereby to impede said forward progress and prevent the engagement of another thread within said hook.

2. A device of the character described comprising a needle having a hook at its free forward end, a latch pivoted to the needle near the hook so that the tip of the latch is movable forwardly to close the hook and rearwardly toward the shank of the needle, and a stop member positioned rearwardly of the latch pivot and forwardly of the tip of the latch when the latch assumes its extreme rearward position, said stop member serving to meet a thread of the fabric during forward progress of the needle thereby to restrain the tip of the latch from proceeding forwardly beyond said thread and hence to prevent premature closing of the latch.

3. A needle for mending knitted fabric comprising a shank, a hook upon the shank, a latch having one end pivotally mounted upon the shank and its free end coacting with the hook whereby a thread looped around the latch and the shank may pass over the point of the latch, and a stop upon the shank located adjacent to the point of the latch when in the open position for engaging a straight thread of the fabric and holding the latter 100 from passing over the point of the latch.

4. A needle for mending knitted fabric comprising a shank, a hook formed upon the end of the shank, a latch having one end pivoted upon the shank and its free end movable in a plane in alignment with the plane of the hook and coacting with the latter, a stop mounted upon the shank and positioned upon the edge of the latter upon which the hook and the latch are positioned, and said stop located adjacent to the point of the latch when it is in the open position for engaging a straight thread of the fabric and holding the latter from passing over the point of the latch when in the open position.

5. A device of the character described comprising a needle having a shank portion adapted to pass through a loop of the fabric to be repaired, a hook at the end of said shank adapted to receive a succeeding thread of said fabric, and a stop member disposed adjacent the shank of the needle and extending transversely thereof, said stop member being constructed and arranged to meet said succeeding thread during forward progress of the needle, thereby to impede said forward progress and prevent the hook from grasping more than one thread.

6. A device of the character described comprising a needle having a hooked end adapt-

ed to engage a succeeding thread of the fabric to be repaired, a resilient clasp extending forwardly along the shank of the needle and terminating short of said hooked end, said clasp being adapted to receive and temporarily retain an existing loop of the fabric, the forward end of the clasp being bent transversely of the needle, thereby providing a stop member adapted to meet a succeeding 10 thread of the fabric during forward progress of the needle, and to impede said forward progress so that only one succeeding thread is engaged by the hooked end of the needle.

In testimony whereof I affix my signature.
